SHADE FIXTURE

Aaron C. Sample, Seattle, Wash.

Application August 5, 1938, Serial No. 223,358

1 Claim. (Cl. 156—28)

The invention relates to a shade fixture and more especially to a window shade raising device.

The primary object of the invention is the provision of a device of this character, wherein a window shade hung upon a window can be conveniently raised and held in an adjusted raised position, the device being hung from the head of the window frame and is located above the shade, centered with respect thereto and connected so that the shade may be unwound from its roller and held in an adjusted position.

Another object of the invention is the provision of a fixture of this character, which is simple in its construction, thoroughly reliable and effective in operation, possessing few parts, being strong, durable, easy of operation and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a fragmentary elevation of a window showing a shade hung thereon with the fixture constructed in accordance with the invention in association therewith.

Figure 2 is an enlarged fragmentary sectional view taken on the line 2—2 of Figure 1 looking in the direction of the arrows.

Figure 3 is a sectional view taken on the line 3—3 of Figure 1 looking in the direction of the arrows.

Figure 4 is a sectional view taken on the line 4—4 of Figure 3 looking in the direction of the arrows.

Figure 5 is a sectional view taken on the line 5—5 of Figure 4 looking in the direction of the arrows.

Similar reference characters indicate corresponding parts throughout the several views in the drawing.

Referring to the drawing in detail, A designates generally a portion of a window frame being of conventional make-up, and B, a window shade, which is carried upon a roller 10 and is adapted to be wound on or unwound from such roller in the adjustment thereof, the roller being of spring winding type and is journaled in shade roller brackets 11, these being fastened to opposite sides of the vertical portions of the window frame. It is preferable to have these brackets 11

support the shade roller 10 approximately midway of the length or height of the window frame A for shading the upper half of such window in the use of the shade.

The fixture constituting the present invention for effecting the adjustment of the shade B comprises a relatively narrow housing 12 forming spaced perpendicular parallel side cheeks 13. This housing 12 is partially closed at its back 14 and bottom 15, respectively, while the front and 10 a portion of the top of the housing is opened and formed with the top area of said housing 12 and projected laterally from the side cheeks 13 thereof are attaching flanges 16 for accommodating fasteners 17 so that the housing can be made 15 secure to the head 18 of the window frame, being preferable to have the housing located at the longitudinal center of said window frame.

Formed in the cheeks 13 of the housing 12 and opening through the free front edges thereof are 20 diagonal slots 19, these being inclined inwardly in the direction of the vertical plane of the window frame A and extend approximately centrally with respect to said housing 12. Removably accommodated within the slots 19 is an axle 20 having a squared terminal 21 which fits one of the slots 19 snugly so that the axle, when engaged in the housing, will be held against rotation. This axle 20 rotatably supports a sprocket pulley 22 over which is trained a link chain 23, its links being engageable by the sprocket teeth of said pulley 22 so that the latter will be positively driven on pulling upon the chain which at one end has connection with the reinforced end 24 of the shade B through the medium of a link 25 loosely engaged in said end and with the end adjacent thereto of the chain. This chain at the other end in this instance has connected therewith a pull string 26, although the same may be 30 dispensed with.

The pulley 22 has formed therewith a disk 27 provided with an annular peripheral flange 28 effecting a recess 29 in this disk and pivoted at 30 to the disk 28 within the recess 29 is a gravity 45 ratchet acting dog 31 adapted to engage in a notch 32 provided in an annular shoulder 33 on the axle 20 for the latching of the pulley 22 on the said axle 20 at determined intervals of rotation of such pulley on making adjustment of the 50 shade B so that it will be held in an adjusted position with relation to the window frame A. The disk 27 of the frame 28 creating the recess 29 effects a boxing for the dog or pawl 31 and the annular shoulder 33 on the axle 20. The pulley 55

is susceptible of free rotation on the axle 20 in one direction and is latched through gravity action of the pawl or dog 31 when rotated in the reverse direction so that the shade can be latched 5 in an adjusted position on unwinding thereof from the roller 10.

The chain 23 has its attachment with the shade at a point vertically aligned with the mounting of the housing 12 on the window frame.

10 What is claimed is:

A shade fixture comprising an upright frame constituting a housing having spaced side walls provided with slots inclined inwardly of the housing and opening upwardly through the said side 15 walls, a center pin passing through the slots and

provided with an angular end contacting with the edges adjacent thereto of one of the slots to hold the pin against rotation, a sprocket rotatably mounted upon the center pin, a gravity actuated dog pivoted to the sprocket, a notched disc fixed to the pin and having the dog engageable with the notch in said disc, and a sprocket chain engaged over the sprocket, said sprocket having an elongated recessed wall accommodating the notched disc and dog and maintaining the chain 10 against riding off the sprocket, being guided between said wall and a side wall of the frame which are arranged at opposite sides of the sprocket.
